APPARATUS FOR MAKING TABLETS

James Albert Raynolds, Jr., Elmhurst, N. Y., assignor to The Atlantic Coast Fisheries Company, New York, N. Y., a corporation of Maine

Application January 19, 1937, Serial No. 121,282

2 Claims. (Cl. 107—8)

This invention relates to tablets for pharmaceutical and other purposes. More particularly, it relates to tablets of a predetermined shape and size and comprising a colloidal matrix having dispersed therein a vitamin-bearing liquid, the vitamin-bearing liquid being completely enveloped in and imprisoned by the matrix so that there is no vitamin-bearing liquid on the exterior surfaces of the tablet. Specifically, this invention contemplates apparatus for producing tablets of the type previously mentioned.

Other objects and the nature of the invention will become apparent from the following description, appended claims and accompanying drawings illustrating one embodiment containing the principles of this invention, and wherein:

Figure 1 is a longitudinal section of one illustrative embodiment of an apparatus employing the principles constituting the present invention.

Figure 2 is a view taken on lines AA of Figure 1. Figure 3 is a detail of a modified form of removing means.

Figures 4, 5, 6 and 7 are plan views of belts showing illustrative molding cavities.

Figures 8, 9, 10 and 11 are longitudinal sections taken on Figures 4, 5, 6 and 7, respectively.

Though the invention is applicable to the various compositions as hereinafter explained, it will be described, for illustrative purposes, in specific detail to the manufacture of gelatin tablets containing a vitamin-bearing liquid dispersed therein, the latter being completely enveloped and imprisoned in the gelatin, there being no free vitamin-bearing liquid on the surfaces of the tablet.

In accordance with the principles of this invention, an aqueous gelatin solution containing a relatively high concentration of gelatin is prepared at an elevated temperature and, while at an elevated temperature, the vitamin-bearing oil is emulsified therein. The emulsion, due to the high concentration of gelatin, is characterized in that it is a viscous liquid at an elevated temperature and upon cooling sets to a firm jelly. After the emulsion has set to a jelly, it must not be disturbed until substantially dry, since crushing, pulling, etc. may damage or otherwise destroy the gel structure with the release of droplets of oil contained therein.

The previously described emulsion is supplied at an elevated temperature to a moving belt containing perforations or cavities of a shape and size conforming to the shape and size of the desired tablets. Immediately after or simultane-

ously with the introduction of the gelatin emulsion into the perforations or cavities, the emulsion in the molding cavities or perforations is chilled with the result that it is set in the form and shape corresponding and conforming to the 5 perforations or cavities.

The tablets may be removed from the perforations or cavities in various manners. For example, when the molding cavities consist of perforations, the molded objects may be ejected by the 10 use of an appropriate pusher or ejector device. If the belt is formed of an elastic material, it may be distorted, such as by stretching or passing over an arcuate or curved surface, whereby the 15 perforations or cavities are enlarged. The distortion may be small, in which case the tablets will be loosened and finally removed by auxiliary means, such as a brush, pusher, etc. Alternately, the distortion may be of such magnitude to permit the tablets to fall under the action of gravity 20 from the belt. Manifestly, the various procedures of removing the molded objects may be used in combination with each other.

In order to effect clean removal of the tablets so that there will be no broken or injured surfaces, a lubricating substance is applied to the 25 perforations or cavities prior to the casting of the gelatin emulsion. Obviously, the lubricant must be of such a nature that it does not deleteriously affect the product or in any way interfere with 30 the operation of the method and apparatus. The lubricant also must be of such a nature that it will not deleteriously affect in any way the belt containing the perforations and molding cavities.

The gelatin emulsion is of the type and nature 35 and composition as set forth in copending application Serial No. 105,086. This emulsion is prepared by dissolving gelatin in warm water to produce a solution of fairly high concentrations, such as 30% to 50% by weight of dry gelatin. 40 To this solution of gelatin, while at an elevated temperature and still liquid, is added, if desired, a plasticizer such as glycerin, glucose, etc. in sufficient quantity to prevent the final product from being too hard and too brittle and to impart the 45 desired degree of softness or elasticity in the final product. In this resulting warm solution of gelatin there is emulsified the vitamin-bearing liquid so that there results an emulsion wherein the gelatin solution constitutes the continuous 50 phase and the vitamin-bearing liquid constitutes the dispersed phase. The water in which the gelatin is dissolved is previously treated, such as by boiling, to remove or expel the oxygen dissolved therein. To make sure that no oxidizing 55

substances exist in the gelatin phase, a reducing substance sufficient to reduce such oxidizing agents may be dissolved in the latter. For this purpose, I find vitamin C, otherwise known as 5 ascorbic or cevitamic acid, to be suitable. If vitamin C is added in excess of the amount required to reduce all oxidizing substances in the gelatin solution, then, of course, the unoxidized excess becomes a therapeutic agent itself. The 10 amount and potency of the vitamin-bearing liquid emulsified in the gelatin solution is based on the potency and liquid content desired in the final product. It is, of course, to be understood that the quantity of oil must be low enough to be 15 wholly dispersed in the gelatin solution without becoming a continuous phase and without exuding the liquid oil in the later stages of the process.

Referring now to the drawings wherein an 20 illustrative embodiment of the apparatus constituting one embodiment of this invention is shown and wherein like reference numerals designate like parts, the reference numerals 1 and 2 designate the vertical and transverse members of a frame formed of any suitable material, such as cast iron, 25 metal and the like, and on which the mechanisms constituting the apparatus, and hereafter fully described, are mounted. The vertical members 1 of the frame may rest upon any support or foundation or they may rest upon the floor 30 of the building wherein the apparatus is to be used. Rollers 3 and 4 are fixedly secured to shafts 5 and 6 respectively which are mounted in bearings 7 carried by the frame. A continuous belt 8, more fully described hereafter, is 35 trained over and is driven by said rollers 3 and 4. The belt 8 is provided with a plurality or series of perforations 9 or cavities 10 constituting molding cavities, the shape and size of which are in accordance with and conform to the size and 40 shape of the finished product. For example, the perforations 9 may be polygonal or rectangular or cylindrical in cross-section, as shown in Figures 4 and 5, and the cavities 10 may be in the form of hemispheres or hemi-ovals as shown in 45 Figures 8 and 10 respectively.

The belt may be formed of any suitable material. Metal, such as steel, silver, nickel, etc., or alloys thereof; synthetic resin compositions; 50 cellulosic derivative compositions; appropriate base materials coated with synthetic resin compositions, cellulosic derivative compositions, etc.; and regenerated cellulose are several illustrative materials of which the belt may be made.

In one preferred embodiment of the invention, 55 the belt 8 is formed of a material, such as, for example, rubber, which can be distorted as by stretching or by passing over a curved or arcuate surface so that the perforations or cavities thereof may be enlarged, with the consequence that 60 the molded objects are loosened therein so that they can be expeditiously removed by auxiliary devices or will drop therefrom by the action of gravity.

The composition which is to be molded is supplied 65 to the perforations 9 or cavities 10 in the belt in any suitable manner. In the embodiment illustrated, the composition is supplied to the perforations or cavities by means of a hopper 11 supported on and carried by the frame. The hopper is movably and adjustably mounted on 70 the frame so that it may be positioned with respect to the belt as may be desired. For obvious purposes, the hopper is also resiliently mounted.

Though it is obvious that the form and shape 75 of the hopper and the means of movably and

yieldingly mounting the same may be effected in various manners and by various means in the present embodiment of the invention, the hopper 11 consists of an appropriately shaped body member 12 having a flared inlet end 13 at the top 5 thereof, the hopper normally being open at the bottom end. If desired, the inlet end 13 may be provided with a cover (not shown). In view of the fact that the composition is to be supplied to the molding cavities or perforations at an elevated temperature, the body member 12 is provided with means to maintain the contents at an elevated temperature. In the form illustrated, the member 12 is provided with a jacket 14, having an inlet 14a and an outlet 14b, whereby steam 10 or some other heating medium of desired temperature may be introduced or circulated there-through.

The hopper 11 is mounted on the frame through the medium of the posts 15 passing through and cooperating with holes of brackets 16 secured at appropriate positions to the said hopper. In the form illustrated, there are four brackets 16, two of which are secured to one side of the hopper adjacent the top and bottom thereof and the other two being similarly secured at similar places to the opposite side of the hopper. As shown, each of the brackets 16 extends beyond the hopper and the extensions are provided with aligned holes through which the posts 15 pass. The lower ends of the posts 15 are fastened in an appropriate manner to the frame of the machine. Preferably, the lower ends are slidably mounted in bearings, whereby the posts 15 may be raised or lowered as desired.

In one embodiment of the invention, the hopper 11 is yieldably and adjustably mounted with respect to the belt 8. Though this can be obtained in various ways, in the form illustrated, it is secured at each post 15 through means of a spring 17, the lower end 18 of which cooperates with the lower bracket 16. The upper end 19 of the spring 17 cooperates with the lower end of a sleeve 20. The upper end of the post 15 is provided with a threaded portion 21 cooperating with a nut 22, whereby upon rotation of the nut the tension of the spring 17, through movement of the sleeve 20, is increased or decreased depending upon the direction of rotation of the nut.

The exit end of the hopper, as previously described, is open and cooperates with the belt 8. The front vertical wall 23 thereof is designed so that it functions as a squeegee. Thus, when the composition is applied to the belt 8 passing beneath the hopper, the squeegee 23 will remove the excess material from the belt and insure complete filling of the perforations or cavities.

Due to the fact that the hopper is slidably mounted on the posts 15, the same is also movable with respect to the belt 8, the degree of movement depending, of course, on the movement of the nuts 22 and sleeves 20 on the posts 15.

If desired, a squeegee (not shown) may be provided in advance of the hopper 11. Such a squeegee may operate in place of or in conjunction with the squeegee 23.

Instead of making the squeegee 23 an integral part of the front wall of the hopper, a slide member functioning as a squeegee may be adjustably, movably and resiliently mounted on the front 70 wall of the hopper in any known manner or as will be apparent to one skilled in the art.

As previously explained, the composition is of a type and nature which sets upon cooling and the invention contemplates means to accomplish 75

- this expeditiously. Various means may be utilized to secure the desired results. For example, I may provide appropriate cooling means which will act directly on the composition in the perforations or cavities in the belt. Likewise, I may provide means which will chill the belt and thereby transmit the cooling effect to the compositions in the perforations or cavities. Also, I may employ combinations of the aforementioned means.
- 10 The chilling means may chill the mold cavities or perforations or belt prior to, simultaneously with, or after the application of the emulsion.

Various chilling mechanisms may be utilized and the invention is not restricted to any particular form or type. In one embodiment of the invention, the desired results are secured by use of a cooler 24 (diagrammatically illustrated in the drawings) in cooperative relationship with the belt 8, which consists of a tank in which a previously fluid medium, previously chilled to the desired temperature, is introduced through the inlet 25 and from which it passes through the cooler chamber 24 and out through the outlet 27.

The cooler 24 may be opened at the top, in which case the belt 8 and a support 28, hereafter described, constitute a moving cover.

It is to be noted that in the illustrated embodiment the cooler 24 extends beyond and underneath the hopper 11 so that the belt 8 is in a more or less chilled state when the emulsion is applied to it.

When the belt is provided with molding cavities, it is unnecessary to provide any means of supporting or maintaining the composition therein. 35 However, when the molding cavities consist of perforations, it is essential that there be provided some means of support to maintain the composition in the perforations until it has been set in the desired form. With this in view, the invention 40 also contemplates the provision of a belt 28 which traverses beneath the belt containing the perforations. This belt is a continuous one and travels at the same rate of speed as the belt 8. It travels over the roller 3, previously described, and also 45 over a roller 29 disposed intermediate the rollers 3 and 4. The roller 29 is fixedly secured to a shaft 30 which is rotatably mounted in bearings (not shown) on the frame of the machine. The supporting belt is formed of a material which 50 possesses a high coefficient of heat transfer. Thus, when this belt is subjected to the cooling operation of the cooler, it is chilled and it effectively transfers the cooling effect directly to the belt 8 and directly also to the composition in the 55 molding perforations, when a belt of the type illustrated in Figures 4 to 7 inclusive is utilized.

The belt 28 is maintained as a support for the belt 8 until the composition in the molding cavities will be chilled and in the firm set condition. 60 If desired, the cooler may be provided with a cover formed of a material having a high coefficient of heat transfer, in which case the supporting belt 28 may be omitted. The cooler is of such length or the time of application thereof to the belt is such that the composition will be set to a firm gel.

When the belt consists of perforations, the molded articles may be removed therefrom in any convenient manner. For example, the belt may 70 pass beneath a brush 31 which rotates in contact with said belt, the action of the brush being sufficient to eject the molded articles from the belt into a collecting hopper 32. If desired, instead of a brush 31 there may be provided a roller having

pins similar to ejector pins suitably disposed around its periphery, so that it may contact with and remove the molded articles coming in contact therewith.

When the molded articles are formed in cavities in contradistinction to the perforations, the belt may be caused to pass around surfaces, whereby it is distorted and the molded articles loosely held therein. Thereafter, the molded materials may be removed by easy brushing of the 10 belt. This embodiment is shown in Figure 3, wherein the belt containing the molded articles passes around the roller 4 and thence over rollers 15 33 and 34. Adjacent the roller 34 there is provided a brush 35 which brushes the molded material from the belt and the removed products are received in a hopper 36. Thereafter, the belt passes over the roller 37 and continues its course over the guide rollers 38, as illustrated. This embodiment may also be used when perforations 20 constitute the molds in the belt.

In order to inhibit the molded materials from adhering to the molding cavities or perforations, with the consequence that the removal thereof is difficult, the invention also contemplates applying to the belt 8 at some stage in the travel thereof, prior to the application of the composition, a substance which functions in the nature of a lubricant. Various substances may be utilized. I have found that oils, such as castor oil or other 30 hydroxylated oils, are admirably suitable for this purpose.

The lubricant, previously described, may be applied to the belt at any convenient point in its path of travel. In the form illustrated, oil is applied to a closed vessel 39 in which rotates a brush 40, the amount of oil being such that the lower portion of the brush is immersed therein and, as it rotates, it applies it on to the surface of the belt. The level of the lubricant in the 40 vessel 39 may be maintained at its desired height in any well-known manner, as, for example, the barometric feed 41.

When a lubricant of the type previously mentioned is used after the molded articles have been 45 collected, they are subjected to a washing to remove any adhering lubricant from the product.

The rollers 3 and 4 may be separately driven, or the roller 3 may be driven by any suitable drive (not shown). In either event, the brush 50 40 is driven by means of a sprocket 42 trained over a sprocket wheel 43, secured to the shaft 5, and a sprocket wheel 44, secured to the shaft on which the brush 40 is mounted. The roller 29 is driven by means of a sprocket chain 45 and sprocket wheels 46 and 47 carried by the shafts 6 and 30 respectively. The brush 35 is driven by the roller 29 through a sprocket chain 48. The other mechanisms or rollers may be connected by sprockets, chains, gears, etc. so that their movement or rotation is synchronized with the rollers 3, 4 and 29.

Though the invention has been specifically described in connection with gelatin tablets containing vitamin-bearing liquids imprisoned therein, it is to be understood that it is equally applicable to tablets containing vitamin-bearing liquids in which the carrier is formed of a colloid matrix other than gelatin. Likewise, the invention is applicable to any composition which sets 70 upon cooling and which can be molded as herein described, such as, for example, candy, cosmetics, plastics, etc.

Although certain preferred embodiments of the invention have been disclosed for purposes of 75

illustration, it is obvious that various changes and modifications may be made therein as will appear to a person skilled in the art. The invention is to be limited only in accordance with the following claims when interpreted in view of the prior art.

I claim:

1. An apparatus which comprises an endless belt having molding perforations formed therein, and adapted to receive the composition to be molded, a second endless belt formed of a material having a high coefficient of heat transfer cooperating with the first-named belt and constituting a support to maintain the composition in the perforations, means to chill the second belt, means to separate the two belts, and means

to remove the molded products from the perforations in the first belt.

2. An apparatus which comprises an endless belt formed of an elastic material and having molding perforations formed therein and adapted to receive the composition to be molded, means to apply a lubricant to said perforations, a second endless belt formed of a material having a high coefficient of heat transfer cooperating with the first-named belt and constituting a support to maintain the composition in the perforations, means to chill the second belt at least while it functions as the support, means to separate the said belts, and means to distort the first-named belt whereby the molded products will be loosened. 15

JAMES ALBERT RAYNOLDS, JR.
